UNITED STATES PATENT OFFICE.

SAMUEL CRUMP, OF NEW YORK, N. Y.

DESIGN FOR A LABEL.

Specification forming part of Design No. 6,327, dated December 24, 1872.

To all whom it may concern:

Be it known that I, SAMUEL CRUMP, of the city, county, and State of New York, have invented a Design for Labels, of which the following is a specification:

The nature of my design is fully represented in the accompanying print, to which reference is made.

a represents an ornamental scroll-border, substantially the same in all its parts, and forming the frame-work of the design. Around this border, and in certain places crossing and recrossing it, is drawn a series of ornamental figures or flourishes, *d*, which inclose and embellish the border aforesaid. Across the face of this design is drawn a plain band or ribbon, *B*, which is curled backward at the ends, and there rolled around the ornamental figures *d* above named. Behind this ribbon, and inclosed and bounded by the scroll-border *a*, is a figure representing a sun-burst, *c*, the center of which is covered by the ribbon *B*, leaving only the upper and lower portions visible. The design complete is composed of two or three

sections, substantially as described, the only material difference between them being that only one section on each design bears the band or ribbon *B*. I purpose making this design in two forms, *X* (having two parts) and *Z*, (having three parts,) as shown, and of various sizes, preserving in all the same general features and distinctive characteristics. I also intend to print the sun-burst figure *c* or omit it, at pleasure; also to print the design in various colors and combinations of colors; but in all cases preserving intact the border *a*, ornament *d*, and ribbon *B* above described, which in all forms will be substantially the same.

Having thus described my design, I claim as new and ask for Letters Patent for—

A design formed of a combination of a scroll-border, a series of ornamental figures or flourishes, and a band or ribbon, substantially as shown.

SAML. CRUMP.
